UNITED STATES PATENT OFFICE

ROBERT L. MACDONALD, OF ROCKFORD, ILLINOIS, ASSIGNOR TO EMERSON-BRANTINGHAM CORPORATION, OF ROCKFORD, ILLINOIS, A CORPORATION OF ILLINOIS

DESIGN FOR AN ELECTRIC HEATER CASING

Application filed May 11, 1931. Serial No. 39,811. Term of patent 3½ years.

To all whom it may concern:

Be it known that I, ROBERT L. MACDONALD, a citizen of the United States, residing at Rockford, in the county of Winnebago and State of Illinois, have invented a new, original, and ornamental Design for an Electric Heater Casing, of which the following is a specification, reference being had to the accompanying drawings, forming part thereof.

In the drawings—

Figure 1 is a perspective view of an electric heater casing showing my new design; and

Figs. 2 and 3 are front and side elevations thereof, respectively.

I claim:

The ornamental design for an electric heater casing, substantially as shown.

ROBERT L. MACDONALD.
